[57] CLAIM

The ornamental design for a rack to assist in the cleaning of seed sorting screens, as shown and described.

DESCRIPTION

FIG. 1 is a perspective view of a rack to assist in the cleaning of seed sorting screens showing my new design;

FIG. 2 is a top plan view thereof;

FIG. 3 is a bottom plan view thereof;

FIG. 4 is a front elevation thereof, which is identical with a rear elevation;

FIG. 5 is a right side elevation thereof, which is a mirror image of a left side elevation.

FIG. 1.

FIG. 2.

FIG. 4.

FIG. 3.

FIG. 5.
